UNITED STATES PATENT OFFICE.

FRITZ ALDENDORFF, OF WILMERSDORF, BERLIN, GERMANY.

AUTOMATIC SWITCH FOR INTERCONNECTING LINES.

Application filed November 28, 1913. Serial No. 803,566.

(GRANTED UNDER THE PROVISIONS OF THE ACT OF MARCH 3, 1921, 41 STAT. L. 1313.)

To all whom it may concern:

Be it known that I, FRITZ ALDENDORFF, a citizen of the German Republic, residing at 23 Barbanterstrasse, Wilmersdorf, Berlin, Germany, have invented certain new and useful Improvements in Automatic Switches for Interconnecting Lines, of which the following is a specification.

My invention relates to machine switching systems and more particularly to quick acting line finders for automatic telephone systems which are capable of connecting to any one of a large group of lines by very short and quick movements of the moving contacts or wipers.

Short movements of the wipers are attained by dividing the contact banks of the finders into sections and arranging the wipers to rest normally at a point between the sections so that when a call is initiated in any section the wipers will immediately commence travelling toward that particular section.

The speed of action of the finders is increased by constructing them of two switches which act simultaneously the one switch choosing the section of the contact bank containing the calling line and the other choosing the subsection in that section.

The motions of the finders are controlled by relays which are in turn controlled by the calling subscribers.

My invention will be fully understood from the following description and by reference to the accompanying drawing in which—

Fig. 1, is a diagrammatic representation of the bank contacts and movable brushes of a line finder and an illustration of the order in which the lines of a group are connected to the bank contacts of the finders belonging to that group.

Fig. 2, shows partly in perspective view and partly diagrammatically the construction of a line finder.

Fig. 3, illustrates the circuits of the subscribers' line and cut-off relays, the connections between the subscribers' line relays and groups of permutation wires used for guiding the line finders to a calling line, and the circuits of a finder starter.

Figs. 4 and 5, represent the circuits of the line finders, and

Fig. 6, shows the circuits of a connector or final selector.

In Fig. 1, are illustrated the ten rows of contacts of a hundred point line finder. The hundred lines of a hundred group are connected in the order indicated by the numbers. For example the lines numbered from 00 to 09 are connected to the bank contacts of the first row. The lines numbered 10 to 19 are connected to the second row of bank contacts and so forth. All the lines with units digits ranging from 0 to 4 are connected to the left half of the contact bank and all the lines with units digits from 5 to 9 are connected to the right half of the bank.

For each row of contacts there is a wiper w_0 to w_9 . The line finder is so arranged that according as the subscriber calling is connected to the left or right half of the contact bank the wipers w_0 to w_9 will move from their middle position to the left or right. The furthest distance that the wipers will have to travel is thus the distance of five contacts.

The wipers w_0 to w_9 are normally insulated so that no connection is made to the calling line by these wipers alone. There is, however, another wiper W that is connected to a trunk or link circuit which operates with the wipers w_0 to w_9 . This wiper W moves towards the upper or lower half of the contact bank according as the calling line appears in the upper or lower half. The wiper W stops moving when it reaches the wiper w_0 to w_9 that is situated in the row containing the bank contacts of the calling line. The greatest number of rows traversed by the wiper W is five. Both the set of wipers w_0 to w_9 and the wiper W travel simultaneously. Therefore the maximum time required for the finding of any one line out of a hundred is the time that a wiper w or W takes to move five steps and the average time required is the time needed for 2.5 steps.

A means which may be used for propelling the wipers w_0 to w_9 is shown in Fig. 2, in which S is a wiper shaft bearing the

wipers w_0 to w_9 and journaled in a bearing b . At the bottom end of the wiper shaft is fixed a disc d . This disc d is driven by another disc d_1 or d_2 fixed to a driving shaft 5 S_1 that may be common to a large number of finders or selector switches. e_1 and e_2 are solenoids which on being energized by an electric current magnetize their respective discs d_1 or d_2 and then attract the outer 10 rim of the flexible disc d to their respective discs d_1 or d_2 . The shaft s_1 with the discs d_1 and d_2 rotates in the direction indicated by the arrow (a) so that when d_1 is magnetized the wipers w_0 to w_9 will rotate to 15 wards the left of the contact bank and when d_2 is magnetized these wipers will be rotated towards the right half of the contact bank. The wipers w_0 to w_9 each consist of a pair of brushes of which the upper 20 one engages with the contacts belonging to the various subscribers contained in its particular row and the lower one slides upon a solid contact piece e. g. p_0 . Each contact piece p_0 to p_9 is connected to the fixed contact of a secondary switch SW. The secondary switch is constructed like the primary switch PS just described except that it has only one row of bank contacts and one wiper W instead of ten. The wiper 25 W is moved by its solenoids or magnets e'_1 or e'_2 towards its lower or upper five contacts connected to the lower or upper five contact pieces p_0 to p_4 or p_5 to p_9 respectively. 30 Fixed to the upper end of the shaft S is a disc d_3 having an oblique slot l at its periphery. Projecting into this slot is a tongue t attached to a switch ds . When the shaft S is rotated in the direction of the arrow a_1 the tongue t slides up onto the top of the disc d_3 and causes the switch ds to close its top contact c_1 , but when the shaft S is turned in the direction of the arrow a_2 the tongue t slides down and rides 40 on the bottom of the disc d_3 and closes the contact c_2 of the switch ds . This switch is used when restoring the finder to its normal position as will be fully described later. The secondary switch SW is also provided 45 with a switch similar to ds , but this is not shown in Fig. 2.

The shaft S of the finder also has a cam d_4 which moves an off normal switch OS the functions of which will be fully described later.

Although for simplicity of illustration only one wiper w and one set of bank contacts per row is shown in Figs. 1, and 2, three wipers and three sets of contacts per row are used, and on the secondary switch SW four wipers W and four sets of bank contacts are provided as shown in the circuit diagram in Fig. 4.

In Fig. 3, S_{00} , S_{04} , S_{05} , etc. represent the 65 subscribers' stations of a group of one hun-

dred subscribers. The stations S_{00} , S_{04} , and S_{05} , S_{09} represent the first and fifth and sixth and tenth stations of the first tens group in the hundred, this tens group being connected to the sets of bank contacts numbered 00 to 09 as shown in Fig. 1. and located in the first row of each line finder of the hundred group. For simplicity of illustration only two stations 04, 05, are shown connected to bank contacts in the lower halves of the contact banks of the finders F_1 F_2 , Fig. 4.

S_{50} , S_{54} , S_{55} and S_{59} represent four stations connected to the upper halves of the finder contacts banks. Of these also only two S_{54} , S_{55} are shown connected to their bank contacts.

The first finder F_1 of the hundred group is represented by four of its ten sets of wipers w^0_a , w^0_b , w^0_c , w^1_a , w^1_b , w^1_c — w^5_a , w^5_b , w^5_c — w^6_a , w^6_b , w^6_c belonging to the primary switch and the set of wipers W^1 belonging to the secondary switch of the finder. The primary and secondary switches each have an additional wiper W_p and W_s . E_1 and E_2 are the motor magnets of the primary switch and E'_1 and E'_2 represent the motor magnets of the secondary switch of finder F_1 . D S₁, Fig. 5 is the switch corresponding to ds , Fig. 2, belonging to the primary switch and D S₂ a similar switch belonging to the secondary switch of the finder F_1 . O S₁ is an off-normal switch on finder F_1 . t_p and s_p are test relays and rl is a release relay of finder F_1 . The release relay controls four switches, r_1 , r_2 , r'_1 , r'_2 which, in order to simplify the drawing, are shown near the motor magnets E that they control. The switches are shown in their normal positions. When the release relay rl is energized it moves these switches from their back contacts to their front contacts.

The finder F_1 is also provided with a connecting relay C R which extends the line of a calling subscriber to the next switch or selector, Fig. 6, the moment the finder has found the calling line.

There are as many finders in a hundred group as required for the moment of maximum traffic. F_2 represents another finder in the same hundred group. Only as many of the parts of this finder are shown as are sufficient to make the system comprehensible. The function of the wipers W_p and W_s of the primary and secondary switch of each finder is to guide the wipers w_a , w_b , w_c and W^1 to the bank contacts that are connected by wires such as 04, 05 etc. to a calling line. The wipers W_p , W_s will therefore be called "guiding wipers." The guiding wipers travel over contacts p_0 to p_9 and p^1_0 to p^1_9 which are connected to two sets of "permutation wires" 0 to 9 and 0¹ to 9¹ the functions of which will be explained presently. The bank contacts p_0 to p_9 and p^1_0 to 130

to p^1 , of all the finders of a hundred group are connected in multiple to the groups of permutation wires, 0—9 and 0¹—9¹. Each hundred group has its own two groups of permutation wires.

Each of the hundred subscribers of a hundred group is connected by a set of multiple wires such as 04 or 05 to a set of bank contacts in each finder F_1 , F_2 of the group, 10 these sets of bank contacts being traversed by sets of brushes w_a , w_b , w_c .

The subscribers' lines are connected to the bank contacts in the order illustrated in Fig. 1. Subscriber S_{00} is connected to the first set of bank contacts in the first row, S_{01} is connected to the second set of contacts in the first row, S_{02} to the third set in first row and so forth. In Fig. 4 only the connections of two subscribers, 04 and 05 in the first row and two subscribers, 54 and 55, in the sixth row of bank contacts are fully shown.

The wipers w^0_a , w^0_b , w^0_c traverse the first row, wipers w^1_a , w^1_b , w^1_c the second row, wipers w^5_a , w^5_b , w^5_c the sixth, wipers w^6_a , w^6_b , w^6_c the seventh row of bank contacts. The wipers and bank contacts of the third, fourth, fifth, eighth, ninth and tenth rows are omitted in order to simplify the drawing.

The wipers w^0_a , w^0_b , w^0_c of the first row are connected by a set of wires w^1_0 to the first set of bank contacts on the secondary switch of the finder, the wipers w^1_a , w^1_b , w^1_c of the second row to the second set and so forth.

In order to connect a certain subscriber's line, say 4, to a trunk line a b c leading to a selector, Fig. 6, all the sets of wipers w^0_a , w^0_b , w^0_c — w^1_a , w^1_b , w^1_c etc. are turned so as to bring one of the sets of wipers e. g. w^0_a , w^0_b , w^0_c onto the set of bank contacts that is connected to the line 04 and the set of secondary wipers W is turned so as to connect to the set of primary wipers e. g. w^0_a , w^0_b , w^0_c that is touching the subscriber's line. The subscriber's line, 04, will then be connected through w^0_a , w^0_b , w^0_c — w^1_0 — W^1 to the trunk a , b , c .

If a calling subscriber's line is connected to a set of bank contacts located in the half of the contact bank shown above the sets of wipers w^0_a , w^0_b , w^0_c — w^1_a , w^1_b , w^1_c etc. a motor magnet E_2 , similar to E_1 , Fig. 2, will come into action and will move all the wipers towards the upper half of the bank. If the subscriber's line is connected to the lower half of the bank the motor magnet E_1 , similar to E_1 , Fig. 2, will be energized and will move all the wipers of the primary switch towards the lower half.

If the calling subscriber is connected to the half of the contact bank shown at the left of the line x — y , the wipers W^1 of the secondary switch will be moved by the mo-

tor magnet E^1 , to the sets of contacts connected to the wipers w^0_a , w^0_b , w^0_c — w^1_a , w^1_b , w^1_c , to w^4_a , w^4_b , w^4_c located at the left of the line x — y and if the calling subscriber is connected to a set of bank contacts situated at the right of the line x — y the wipers W^1 will be moved by the motor magnet E^1 towards the secondary bank contacts that are connected to the sets of wipers w^5_a , w^5_b , w^5_c to w^9_a , w^9_b , w^9_c located at the right side of the line x — y .

The direction of movement of the wipers is thus dependent on the part of the finder contact bank that a calling subscriber is connected to. The subscribers unconsciously determine these directions of movement by means of relays m_1 , m_2 , and m^1_1 , m^1_2 and by circuits connected to their line relays 1_{00} , 1_{04} etc.

The relays m_1 , m_2 determine the direction of movement of the primary switch wipers w^0_a , w^0_b , w^0_c etc. and the relays m^1_1 , m^1_2 determine the direction of movement of the secondary switch wipers W^1 .

All the subscribers with units digits ranging from 0 to 4 are connected to the bank contacts shown in Fig. 4, in the lower half of the bank. Therefore all these subscribers are arranged to control by the first lower armature contacts 100 of their line relays the circuit (d_0) of the relay m_1 which closes the circuit of the motor magnet E_1 and thus causes the downward movement of the wipers of the primary switch.

The corresponding line relay contacts 100 of all the subscribers with units digits ranging from 5—9 are connected to the circuit U of the relay m_2 that closes the circuit of the "upward motion magnet", E_2 , for all the subscribers with these units digits are connected to the upper half of the bank.

All the subscribers of the group with tens digits ranging from 0 to 4 are connected to bank contacts shown in Fig. 4, at the left side of the line x — y , the wipers W^1 of the secondary switch are moved towards the wipers w_a , w_b , w_c , etc., by the motor magnet E^1 which is controlled by the relay m^1_1 . Therefore all the subscribers with tens digits ranging from 0 to 4 are connected by the contacts 101 of their line relays to the circuit l_0 connected to the "leftward motion relay" m^1_1 .

All the subscribers with tens digits ranging from 5 to 9 are connected to bank contacts shown at the right side of line x — y in Fig. 4. The motor magnet E^1 that causes the wipers W^1 to travel towards the primary wipers in the right half of the bank is controlled by the "rightward motion relay" m^1_2 and therefore all the subscribers with tens digits ranging from 5 to 9 are connected by their armature contacts 101 to the circuit (r_0) of the rightward motion relay m^1_2 .

I. is thus seen that the relays m_1 , m_2 indicate whether the calling subscriber is connected to the upper or lower half of the contact bank and that the relays m^1_1 , m^1_2 indicate whether the subscriber is in the right or left half of the bank.

The relays m_1 , m_2 , m^1_1 , m^1_2 taken together indicate what quarter of the contact bank the subscriber is in. If the subscriber is in the lower left hand quarter for example the relays m_1 and m^1_1 would be energized so as to energize the motor magnets E_1 and E^1_1 .

The particular line in the quarter of the contact bank indicated by the relays m_1 , m_2 , m^1_1 , m^1_2 is indicated by means of the permutation wires 0 to 9 and 0^1 to 9^1 . The permutation wires 0 to 9 determine the point p_0 to p_9 at which the primary guiding wiper W_p shall stop and the permutation wires 0^1 to 9^1 determine the point of stoppage of the secondary guiding wiper W_s .

The permutation wires 0 to 9 and 0^1 to 9^1 correspond to the tens and units digits respectively of the calling subscribers. The contact 102 of the line relay l_{50} of subscriber 00 is connected to the units permutation wire 0 and contact 103 of this relay is connected to the tens permutation wire 0. The contacts 102 and 103 of the subscriber 01 are connected to tens permutation wire 0 and to units permutation wire 1, respectively. Thus the connections between the permutation wires and the line relay contacts 102 and 103 of the hundred subscribers are such as to produce one hundred different permutations, and each permutation represents a different combinative setting of the primary and secondary switches of a finder F_1 , F_2 . Thus if subscriber 05 calls the primary switch of the finder will be moved so as to bring the guiding wiper W_p into connection with the units permutation wire 5 and the secondary guiding wiper W_s will be moved into connection with the tens permutation wire 0 and as the sets of brushes w^0_a , w^0_b , w^0_c — w^1_a , w^1_b , w^1_c etc. and W^1 are moved in unison with their guiding wipers the subscriber 05 would be connected through the sixth set of bank contacts that is connected in the first contact row to the wires 05 and through w^0_a , w^0_b , w^0_c — w^1_a — W^1 to the trunk a , b , c .

It will now be assumed that a subscriber e. g. No. 59 makes a connection with another subscriber.

When the calling subscriber S_{59} removes his receiver from the switchhook he closes his line loop a_{59} , b_{59} in a well known manner and his line relay l_{59} is then energized by a current flowing from the negative pole of the exchange battery through the contact 110 of the finder starter F S, common feed wire 111, contact 105 of line relay l_{59} , 112, b_{59} , a_{59} , 113 to earth. Line relay l_{59} is ener-

gized and opens its contact 105 whilst closing its contacts 100, 101, 102, 103 and 104.

Since the subscriber S_{59} is connected to a set of bank contacts located in the upper half of the contact bank and to the right of the line x — y the upward motion relay m_2 and the rightward motion relay m^1_2 must be energized in order to set the finder onto the calling line. Therefore the armature contacts 100 and 101 of the line relay l_{59} are connected to the circuits u and ri and the relays m_2 and m^1_2 are energized by circuits from the negative pole of the battery through F S, m_2 , u , 100 to earth and from the negative pole through m^1_2 , ri , 101 to earth. At the same time the tens permutation wire 5^1 and the units permutation wire 9 are earthed by contacts 103 and 102 respectively.

The upward motion relay m_2 closes its armature contact 114 and prepares a circuit for the upward motion magnet E_2 and the rightward motion relay m^1_2 prepares a circuit at its contact 115 for the rightward motion magnet E^1_2 . The finder starter F S is energized in series with the relay m_2 and by attracting its armature 116 momentarily closes the contact 117. This causes a current impulse to flow from the negative pole through 117, starting wire S_t , contacts 118, 119 of the off-normal switch of the first idle finder (e. g. F 1), wires 123 and 124, magnets E^1_1 and E^1_2 , contacts 128 and 132, wires r , i , u_1 , contacts 115 and 114. The magnet E^1_2 is energized and moves the wipers W^1 , W_s of the secondary switch one step towards the right hand wires w^1_5 , w^1_6 and the magnet E_2 is also energized and moves the wipers w^0_a , w^0_b , w^0_c — w^1_a , w^1_b , w^1_c , etc., and the guiding wiper W_p of the primary switch one step upwards.

It will be assumed for convenience of description that the magnets E_1 , E_2 , E^1_1 , E^1_2 move their wipers by a step by step ratchet and pawl device so that for each impulse sent through these magnets their wipers are moved to another set of bank contacts.

It will be noticed that two magnets E_1 and E_2 are connected to the wire 123 and two magnets E^1_1 , E^1_2 to the wire 124. The impulse sent from the finder starter F S over the starter wire S_t will, however, always affect one of the magnets E_1 or E_2 , and one of the magnets E^1_1 or E^1_2 only, because there will always be only one circuit of each pair of motor magnets closed by the relays m_1 , m_2 , m^1_1 , m^1_2 .

On the primary switch of the finder being moved out of its normal position the off-normal switch $O S_1$ closes its contacts 120, 121 and 122 and opens its contacts 118 and 119. The primary switch is arranged to execute its initial movement when the starting impulse over the starting wire S_t ceases, so

that the contact 121 through which the starting wire is extended to the next finder F_2 is not closed before the starting impulse ceases and a false starting of the next finder F_2 5 does not occur.

When the contact 122 is closed an interrupter 133 is connected to the motor magnets in place of the starting wire and current impulses then flow from the negative pole through 133, 134 to the wire 138. From 10 the wire 138 the impulses flow through the wires 139 and 140 to the pairs of magnets E_1 , E_2 — E_1' , E_2' . Only the circuit of one magnet in each pair is closed by the relay 15 m_1 , m_2 , m_1' , m_2' at any one time. In the case assumed the circuits of magnets E_2 and E_2' are closed at 114 and 115 respectively. Therefore the impulses flowing 20 through the wires 139 and 140 will energize only the magnets E_2 and E_2' causing the wipers of the primary and secondary switches to be both moved upwardly as shown in Figure 4.

It may of course happen that both switches 25 will move downwardly, or that the primary switch will move its wipers downwardly whilst the secondary switch moves its wipers upwardly and vice versa.

In the case assumed the wipers W_1 will 30 move upwards one step and the circuit of the magnet E_2' will then be broken by the energization of the secondary test relay sp , for a circuit will be established for this relay by the secondary guiding wiper W_s reaching 35 the tens permutation wire 5¹. This circuit may be traced from the negative pole through 141, 142, sp , W_s , p_1^5 , 5¹, 143, 103 to earth. Once the energization of relay sp the circuit of magnet E_2' is broken at 136 40 and the motion of wipers W_1 , W_s is stopped.

The wipers of the primary switch will 45 continue their movement until the guiding wiper W_p reaches an earthed permutation wire, which in the case assumed will be when the permutation wire p^9 is reached. The 50 circuit of the primary test relay will then be closed from the negative pole through 141, tp , W_p , p^9 , 144, 102 to earth, and the test relay tp will open the circuit of the 55 magnet E_2 at contact 135, thus stopping the operation of this magnet. The wipers w_1^5 , w_1^5 , w_1^5 will now be resting on the set of bank contacts bc_5^9 to which subscriber S_5^9 is connected, and the set of wipers W_1 will 60 be resting on the secondary switch contacts connected by w_1^5 to w_1^5 , w_1^5 , w_1^5 . Thus the calling line will be connected through its wires 59, bc_5^9 , w_1^5 , w_1^5 , w_1^5 — w_1^5 , W^1 to the trunk abc .

65 The moment both test relays sp , tp are energized, a circuit is closed from the negative pole through 137, 145, C_R to earth and the connecting relay C_R then closes its contacts 146, 147, 148, 149 whilst opening

its contact 134. By the closure of contacts 148, 149 the calling line is extended to the selector Sel and the closure of the contact 146 results in the energization of the calling subscriber's cut off relay co_{59} by a current from earth through C_R , 149¹, 146, c^1 , middle brush of W^1 , w_1^5 , bank contact of line 59 on which w_1^5 is resting, wire c_{59} connected to this bank contact, cut off relay co_{59} to the negative pole of the battery. The cut off relay is energized and cuts the line relay l_{59} off of the calling line a_{59} , b_{59} , thus deenergizing the line relay.

As long as a line relay is energized the upward motion relay m_2 or the downward motion relay m_1 will be energized in series 80 with the finder starter and the finder starter will keep open the common battery feed 111 to all the line relays of the hundred at 110 and thus prevent any other subscriber in the group from calling. But this condition 85 only lasts until a finder F_1 , F_2 , etc. has made a connection with the calling line and as the average time required for this is the time that it takes the wipers to execute 2.5 steps the blocked condition of all the lines except 90 the first one to send in a call only lasts a fraction of a second and a second subscriber sending in a call would not notice any delay.

When the line relay l_{59} of the calling line 95 is deenergized by the energization of the cut off relay co_{59} it opens its locking circuit contact 104, the circuits of the motor magnet control relays m_2 and m_1' , and the earth connections of the permutation wires 100 5¹ and 9. The finder starter F_S is also de-energized and the common battery feed 111 closed at 110. The falling off of the armature 116 does not cause a closure of the starting circuit at 117.

The opening of the earth connections of the permutation wires 5¹ and 9 results in the deenergization of the test relays sp and tp and in the closure of the motor magnet circuits at 135 and 136, but no operations of 110 the motor magnets is possible because their circuits are now open at another contact 134.

The connecting relay is maintained energized by the current flowing through it and the cut off relay co_{59} . Another circuit closed 115 by the energization of relay C_R may be traced from earth through C_R , 149¹, 147, c^1 , 155 to the negative pole whereby the relay 155 is energized and closes its contact 156 thus preparing the circuits of the selector 120 controlling relays R_R and C_R , as will be presently described.

By the closure of the contacts 148, 149 the line control relay L_R is connected to the calling line S_{59} and is energized in a circuit 125 including the calling subscriber's line loop. This circuit is from the negative pole of the exchange battery through the lower winding

of L R, b^1 , 149, b , b_8 , wb^5 , b_{59} , S_{59} , a_{59} , w^5 , a_8 , a , 148, a^4 , upper winding of L R, to earth.

If the calling subscriber desires a connection with subscriber No. 78 he will by means of his selector controller first cause seven openings of his line loop and then cause eight such openings. Until the calling subscriber commences working his selector controller the line control relay L R remains energized and closes a circuit for the release relay R R from the negative pole through 156, 180, R R, 181, 176, 182 to earth. The seven rapid openings and closings of the line control relay circuit result in seven openings of the contact 176 and the "change over relay" C R₁ is then energized by a current from the negative pole of the battery through 156, R R, C R₁ to earth. The relay L R is so adjusted that during the oscillations of its armature the contacts 175 and 176 are scarcely closed and if they are closed at all the closures are of the shortest possible duration. The relays R R and C R₁ are thus maintained energized whilst the selecting impulses are flowing. The contact 174 is so adjusted as to be closed during a considerable period of each oscillation. Each time the contact 174 is closed a current impulse flows from the negative pole through 156, 174, 171, 178 vertical magnet V M of the selector Sel, which is assumed to be of the well known up and around type, to earth. The wipers of the selector are thus stepped up to the seventh row of bank contacts. A pause now ensues during which the line control relay pulls up its armature steadily and short circuits the "change over relay" C R₁ causing this to release its armature 177. The off normal contact 172 is closed when the selector executes its first upward step so that the closure of 177 results in a current flowing from the negative pole through 156, 173, 183, 177, 172, side switch magnet S¹ M to earth. The side switch magnet immediately shifts the arms 178, 179 to their second positions and thus effects the "change over" of the stepping or measuring circuit (156, 174, 184, 171) from the vertical magnet V M to the rotary magnets R M.

When the next series of impulses is now sent in the closings of the contact 174 result in impulses flowing from the negative pole through 156, 174, 184, 171, 178, R M, to earth. As the calling desires connection with the eighth subscriber in the seventh contact row the wipers wsa, wsb, wsc are stepped round eight steps and then rest upon line No. 78 which is connected to wires similar to a_{59} , b_{59} , c_{59} , leading to the desired subscriber No. 78. When the pause ensues after the second series of impulses the change over relay CR₁ is again deenergized by the short circuit at contact 176 and the side switch magnet is again energized by a

current from the negative pole through 156, 173, 183, 177, 172 to the side switch magnet S¹ M and earth. The side switch now changes over the rotary magnet control function to the testing function by closing the test circuit from earth through the switch arm 179, 160, 190, wsc, c₇₈, cut off relay co₇₈ (not shown but similar to co₅₉) to the negative pole. If the wanted line is free the test relay 190 will receive sufficient current to energize it and will close its armature contacts 164, 165. By closing its contact 165 it short circuits a part of winding and reduces the potential on the test wire c₇₈ sufficiently to prevent the test relay of any other selector that may try to make a connection with the busy line from attracting its armature.

The closure of the test relay contact 164 causes the application of the ringing machine R¹ M to the wanted line so that ringing current flows from earth through R¹ M, ringing control relay R¹ R, 164, 169, wsa, a₇₈, wanted subscriber S₇₈, b₇₈, wsb, 166, interrupter 192 to the negative pole.

When the called subscriber responds by removing his receiver from the switchhook the ringing current flowing through relay R¹ R is strengthened sufficiently to energize it, so that it closes its armature contact 163 and energizes a relay 193 by a current from earth through 163, 193 to the negative pole.

The relay 193 then opens the ringing current circuit at contacts 169, 166 and connects the calling and called lines together at contacts 168, 167, so that the conversation between the two subscribers may now take place.

When the subscribers replace their receivers on their switchhooks and thus open their line loops the line control relay LR is deenergized and the short circuiting contact of the release relay RR is permanently closed. The release relay then allows its armature to fall back and closes its armature contact 170 whereby the release magnet Rel of the selector Sel is energized in a circuit from the negative pole through 170, Rel, off normal contact 161, which was closed when the selector executed its first movement, to earth. This circuit remains closed until the selector has regained its normal position.

The release magnet in addition to releasing the selector Sel opens its test circuit at 160 and thus prevents the application of test potential to lines touched by the wipers wsa, wsb, wsc during the restoration of the selector. The release magnet also closes contacts 158, 159. By the closure of 159 the connecting relay CR is short circuited and the contacts 146, 147, 148, 149 are opened and the relays co₅₉ and 155 deenergized.

By the closure of 158 the release relay r₁ 130

of the line finder is energized by a current from earth through 158, rl to the negative pole. The release relay rl closes a locking circuit for itself from the negative pole 5 through rl , 157, 120 to earth. It opens the battery connection to the finder test relays sp , tp to prevent these relays from acting during the restoration of the finder to its normal position. The release relay rl also 10 opens the contacts 125, 128, 129, 132 thereby making the circuits of the motor magnets independent of the relays m^1 , m_2 , m_1^1 , m_2^1 .

The restoration of the finder F^1 to its normal position is now accomplished by the motor magnets E_2 , E_2^1 that operated in setting the finder onto the calling line. Only the 15 circuits of these two magnets will be closed because the direction of movement of the primary and secondary switches was such as to cause the closure of the contacts C_2 and C_2^1 of the switch DS_1 and DS_2 , which it will be remembered are constructed like the switch ds in Fig. 2.

Therefore restoring impulses will flow from the negative pole through 133, 122, 134, 138, 135, 139, E_2 , C_2 , DS_1 to earth and from the negative pole through 133, 122, 134, 138, 136, 140, E_2^1 , C_2^1 , DS_2 to earth. 20 When the primary and secondary switches of the finder reach their normal positions the switches DS_1 and DS_2 assume their middle positions in which none of 25 their contacts are closed. The off-normal switch OS_1 will then also have opened its contacts 122, 121, 120 and closed its contacts 118, 119. The opening of the contacts of the switches DS_1 , DS_2 results in the 30 primary and secondary switches of the finder stopping in their normal positions and the opening of the contact 120 causes the release relay rl to be deenergized and the 35 circuits of the motor magnets E_1 , E_2 , E_1^1 and E_2^1 to be reconnected to the wires do_1 , u_1 , le^1 and ri^1 controlled by the relays m_1 , m_2 , m_1^1 , m_2^1 .

The finder F_1 is now ready to be used for another call.

As long as the finder F_1 is not in readiness for a call all calls coming in will be passed through the contact 121 to the next finder F_2 over the extension starting wire S^4 and if this finder is also in use the calls will be passed to the next ready finder 55 through the contact 200.

Having thus fully described my invention I claim:

1. In combination, two groups of lines, a switch for connecting a line in one of said 60 groups with a predetermined line in the other group, means for moving said switch in a certain predetermined direction to connect certain ones of said predetermined lines, and means for moving said switch in

another direction for connecting with certain other predetermined lines.

2. A group of lines, a switch having a movable contact, a fixed contact for each of said lines, said contacts being arranged in sections, said movable contact being arranged to be moved in the act of making a connection with a line in the direction towards one section of contacts and in the opposite direction towards another section of contacts.

3. A group of lines, a switch having a bank of contacts each contact being connected to a said line, the bank of contacts being divided into sections, a movable contact in said switch, normally situated between the 80 said sections, a magnet for driving the movable contact towards one section of bank contacts and another magnet for driving the movable contact towards another section of bank contacts in the act of making a 85 connection.

4. A switch having a bank of contacts divided into two sections with the dividing line in one direction and into two sections with the dividing line in a second direction, 90 a movable contact capable of moving in the one direction towards one of the sections with the dividing line in the one direction and capable of moving in another direction towards the other section with the same dividing line, and another movable contact capable of moving in the one direction towards one of the sections with the dividing line in the second direction and capable 95 of moving in another direction towards the other section with the said dividing line in the said second direction.

5. In a switch, a bank of stationary contacts, differently designated lines terminating in said contacts, movable contacts co-operating with said stationary contacts, means for moving said movable contacts in different directions to connect with the stationary contacts of a line, and means dependent on the designation of the line to be connected with for determining the direction of movement of said movable contacts.

6. In a switch, a row of fixed contacts, a movable contact normally resting in the middle of said row of fixed contacts, means for driving said movable contact from the middle of said row in one direction, means for driving said contact from the middle of the row in the opposite direction, a second row of fixed contacts, a second movable contact normally resting in the middle of said second row, means for driving the said second movable contact in one direction, and means for driving said second movable contact in the opposite direction.

7. In combination, a plurality of subscriber's lines, a line finder having a plurality of stationary contacts in which said

lines terminate, movable contacts for said finder, means responsive to the initiation of a call on a certain line for moving said contacts over the stationary contacts of certain 5 predetermined portion of said lines including the calling line, and means responsive to the initiation of a call on another line for moving said movable contacts over the stationary contacts of the balance of the lines, 10 including said other line.

8. A group of lines, a plurality of switches each having a movable contact, a fixed contact for each of said lines, said contacts being arranged in sections, said movable contact being arranged to be moved in the act 15 of making a connection with a line in the direction toward one section of contacts and in the opposite direction towards another section of contacts.

9. In a telephone exchange system, a plurality of subscribers' lines, a plurality of trunk lines, a switching device comprising two contacts and a plurality of conductors, means for operating one contact to connect 25 a calling line with a conductor, and means for operating the other contact for connecting a conductor with an idle trunk line.

10. In a telephone exchange system, a plurality of subscribers' lines, a plurality 30 of trunk lines, a switching device comprising two sets of contacts and a plurality of conductors, means operative upon the initiation of a call for actuating contacts of one set to connect the calling line with a conductor and simultaneously operating contacts of the other set for connecting an idle trunk line with said last mentioned conductor.

11. A group of lines, a plurality of 40 switches each having a bank of contacts, each contact being connected to a said line, the bank of contacts being divided into sections, a movable contact on each said switch normally resting between two sections, a 45 magnet for driving the movable contact towards one section of bank contacts and another magnet for driving the movable contact towards another section of bank contacts in the act of making a connection.

12. A group of lines, relays controlled by said lines, a switch having a bank of contacts divided into sections, a movable contact normally resting at a point between two said sections, magnets for driving said 55 movable contact in different directions towards said sections and controlled by said relays.

13. A group of lines, relays controlled by said lines, a switch having banks of contacts divided into sections, movable contacts normally resting at points between sections, magnets for driving said movable contacts in different directions towards said sections and controlled by said relays.

14. A group of lines, relays controlled

by said lines, a plurality of switches each having banks of contacts divided into sections, movable contacts normally resting at points between sections, magnets for driving said movable contacts in different directions 70 towards said sections and controlled by said relays, starting means for starting a switch by the said relays, means for causing a switch to connect only to the line from which it received the starting impulse. 75

15. A switch comprising a bank of contacts divided into sections, a movable contact normally resting between said sections, means for moving said movable contact towards one of said sections, means for moving said movable contact towards another of said sections and means for stopping said movable contact on a contact in a said section. 80

16. A group of lines, a plurality of switches each comprising a bank of contacts divided into sections, a movable contact normally resting between said sections, means for moving said movable contact towards one of said sections, means for moving said movable contact towards another of said sections and means for stopping said movable contact on a contact in a said section. 85

17. A group of lines, relays controlled by said lines, a switch comprising a bank of contacts divided into sections, a movable contact normally resting between said sections, means controlled by said relays for moving said movable contact towards one of said sections, means controlled by said relays for moving said movable contact towards another of said sections and means controlled by said relays for stopping said movable contact on a contact in a said section. 90

18. A group of lines, relays controlled by said lines, a plurality of switches each comprising a bank of contacts divided into sections, a movable contact normally resting between said sections, means controlled by said relays for moving said movable contact towards one of said sections, means controlled by said relays for moving said movable contact towards another of said sections and means controlled by said relays for stopping said movable contact on a contact in a said section, starting means for starting a switch by the said relays, means for causing a switch to connect only to the line from which it received the starting impulse. 110

19. A switch comprising a bank of contacts divided into sections, a movable contact normally resting between said sections, means for moving said movable contact towards one of said sections in the act of connecting, means for moving said movable contact towards another of said sections in the act of connecting and restoring means 115

for moving the movable contact in the same direction whilst restoring as it did in the act of connecting.

20. A group of lines, a plurality of switches each comprising a bank of contacts divided into sections, a movable contact normally resting between said sections, means for moving said movable contact towards one of said sections in the act of connecting, 10 means for moving said movable contact towards another of said sections in the act of connecting and restoring means for moving the movable contact in the same direction whilst restoring as it did in the act of 15 connecting, starting means for starting a switch by the said relays, means for causing a switch to connect only to the line from which it received the starting impulse.

21. A switch comprising a bank of contacts divided into sections, a movable contact normally resting between said sections, means for moving said movable contact towards one of said sections, means for moving said movable contact towards another 25 of said sections and restoring means for causing one of said moving means to move the movable contact into its normal position.

22. A group of lines, a plurality of switches each comprising a bank of contacts divided into sections, a movable contact normally resting between said sections, means for moving said movable contact towards one of said sections, means for moving said movable contact towards another 35 of said sections and restoring means for causing one of said moving means to move the movable contact into its normal position, starting means for starting a switch by the said relays, means for causing a switch to connect only to the line from which it received the starting impulse.

23. A group of lines, relays controlled

by said lines, a switch comprising a bank of contacts divided into sections, a movable contact normally resting between said sections, means controlled by said relays for moving said movable contact towards one of said sections, means controlled by said relays for moving said movable contact towards another of said sections and restoring means for causing one of said moving means to move the movable contact into its normal position.

24. A group of lines, relays controlled by said lines, a plurality of switches each comprising a bank of contact divided into sections, a movable contact normally resting between said sections, means controlled by said relays for moving the said movable contact towards one of said sections, means controlled by said relays for moving said movable contact towards another of said sections and restoring means for causing one of said moving means to move the movable contact into its normal position, starting means for starting a switch by the said relays, means for causing a switch to connect only to the line from which it received the starting impulse.

25. In combination, a plurality of telephone lines, a switch in which said lines terminate in a certain order, means for operating said switch to select and seize any one of said lines when calling, means for restricting all selecting operations of said switch to a relatively small number of lines but always including the calling line.

In witness whereof I have signed this specification in the presence of two witnesses.

FRITZ ALDENDORFF.
